[57] CLAIM

The ornamental design for a fluid cartridge for a cleaning tool or the like, as shown.

DESCRIPTION

FIG. 1 is a top plan view of a fluid cartridge for a cleaning tool or the like showing our new design;
FIG. 2 is a front elevational view thereof;
FIG. 3 is a right side elevational view thereof;
FIG. 4 is a rear elevational view thereof;
FIG. 5 is a left side elevational view thereof; and
FIG. 6 is a bottom plan view thereof.
